US00D920256S

(12) **United States Design Patent** (10) **Patent No.:** **US D920,256 S**
Turksu et al. (45) **Date of Patent:** **** May 25, 2021**

(54) **CONNECTOR PLUG FOR COMPUTER PORT**

(71) Applicant: **SARIANA, LLC**, San Diego, CA (US)

(72) Inventors: **Alan Turksu**, San Diego, CA (US);
Mustafa Burak Guclu, San Diego, CA (US)

(73) Assignee: **SARIANA, LLC**, San Diego, CA (US)

(**) Term: **15 Years**

(21) Appl. No.: **29/699,800**

(22) Filed: **Jul. 29, 2019**

Related U.S. Application Data

(63) Continuation of application No. 29/691,703, filed on May 17, 2019, now Pat. No. Des. 910,578.

CLAIM

The ornamental design for a connector plug for computer port, as shown and described.

DESCRIPTION

FIG. 1 is a top, left, rear perspective view of a connector plug for computer port showing our new design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a rear elevational view thereof;

FIG. 7 is a front elevational view thereof; and,

FIG. 8 is a top, front right perspective view thereof.

The broken lines in the figures represent portions of the connector plug for computer port which form no part of the claimed design.

1 Claim, 4 Drawing Sheets
